UNITED STATES PATENT OFFICE.

GEORGE L. ROBINSON AND JAMES DEAN, OF SANTA MONICA, CALIFORNIA.

DOOR-HOLDER.

No. 911,074.

Specification of Letters Patent.

Patented Feb. 2, 1909.

Application filed August 13, 1908. Serial No. 448,656.

To all whom it may concern:

Be it known that we, GEORGE L. ROBINSON and JAMES DEAN, citizens of the United States, residing at Santa Monica, in the county of Los Angeles and State of California, have invented certain new and useful Improvements in Door-Holders, of which the following is a specification, reference being had therein to the accompanying drawing.

This invention relates to improvements in combined holders and checks or bumpers, and has for its object the provision of means for facilitating the holding of a door in a closed position.

Another object of the invention is the peculiar construction of a combined holder and bumper, which is adapted to be used in connection with any spring-actuated door, and is especially constructed for and adapted to be used with screen-doors.

It is well known that with screen-doors of the ordinary type, when they are swung closed by the action of their spring or spring-hinges, said doors often fly back and remain sufficiently away from the door-frame or jamb to leave a crack for the entrance of insects, and, consequently, another object of our invention is to provide a device which will avoid this objection, which device will not only serve to prevent the door from slamming violently, but will serve to prevent any rebound, and also which device will hold the door tightly shut until it is desired to manually open the same.

With these and other objects in view, the invention consists of certain novel constructions, combinations, and arrangements of parts, as will be hereinafter fully described and claimed.

In the drawings: Figure 1 is a perspective view of a device constructed in accordance with our invention. Fig. 2 is a front view, showing the same applied to a support and in position as it appears when actually holding a door closed, and Fig. 3 is a vertical, sectional view taken on line 3-3, Fig. 2. Fig. 4 is a plan view of the blank prior to folding for forming the frame or casing.

Referring to the drawings by numerals, 1 designates the sides of the frame or casing, and 2 the back thereof. The sides and back are each provided with a right-angled integral apertured lug 3, through which extends any suitable fastening means, as for instance,

screw 4, when the casing or frame is secured to the door-frame or jamb 5.

Tongue or lug 6 is integral with the intermediate portion or back 2 of the frame, and said tongue is positioned parallel with the sides 1, 1, and is provided with an aperture 7. The tongue 6 is formed intermediate the ends, and preferably, at the center of the back or intermediate portion 2, for the purpose hereafter described.

We, preferably, form the casing or frame from a single sheet-metal blank by forming substantially V-shaped notches 8 in one end and cutting the outer edges, at 9, away, for producing the substantially V-shaped lugs 3. The corners of the blank, at the opposite end, are also cut at an angle, as at 10, for minimizing the weight of the casing. The tongue 6 is substantially V-shaped, and is partly cut from the body of the blank, and as said tongue extends transversely of the intermediate portion or back 2, it will be seen that when the blank is bent to the shape shown in Fig. 1, the tongue will be positioned parallel with and between the sides 1, so that when the spring 11, hereinafter specifically described, is attached, through the medium of aperture 7, to the tongue 6, the strain will be in an imaginary line parallel with the body of the tongue, instead of at right-angles, as would be the case if the tongue was not parallel with the sides, but at right-angles thereto; the peculiar construction and positioning of the tongue increases the life of the structure, as the amount of strain exerted upon the lug by the spring will not affect its position nor decrease its efficiency.

A pair of crescent-shaped arms 12 are pivotally mounted upon rivets 13, which rivets extend not only through the crescent-shaped arms, but also through the sides 1. Rivets or shafts 14 connect the outer ends of the pivotally-mounted arms 12, and upon these rivets or shafts are rotatably mounted rollers 15 and 15*, which are, preferably, formed of yielding material, as for instance, rubber. The outer rubber roller 15 is adapted to be engaged by the frame of the door 16, whereas the inner roller 15* constitutes a buffer for taking the jar off of the rivets 13, when the door 16 is closed violently, as it will be seen upon referring to Fig. 3; that the inner ends of the arms 12 do not normally engage the back or intermediate portion 2 of the frame or casing, as this is undesirable. Further-

more, by having the rubber buffer 15^a at the inner ends and between the arms 12, the closing of the door is accomplished without practically any noise, for the reason that if 5 the inner roller 15^a was removed, or not employed, a very inefficient structure would be produced, because the tension of the spring 11 is sufficient to cause the inner ends of the arms to hit against the back 2 and strain the 10 rivets 13, to say nothing at all about the noise which would accompany this operation, whereas this is obviated by the roller 15^a.

The spring 11 is provided with hooks, at 15 each end, and one of the hooks is passed through the aperture 7 of the tongue or lug 6, and the hook at the other end is faced over a rivet or connecting member 17, which is supported upon the outwardly-curved or 20 crescent-shaped arms 12, between the outer shaft carrying the roller 15 and the rivets 13. Therefore, it will be seen that the spring is 25 under the greatest strain when the arms 12 are in the position shown in Fig. 1, or in other words, when the device is in its open or 30 set position, whereby the door could be swung outward or to an open position, but upon the door being closed, the same will strike against the roller 15^a and causes the outer roller 15 to engage the door for holding 35 the same closed. Consequently, it will be seen that roller 15^a also performs another function, to wit: acts as a bumper for the door to first engage before said door has been moved to its closed position, thereby obviating 40 the jarring of the door, as would be the case if the door came in engagement with a metallic arm. It is not necessary to injure the door when closing the same, nor is it necessary to place a metallic reinforcing plate or 45 member upon the door, when the rubber or yieldable roller or buffer 15^a engages the same. Furthermore, it will be apparent that when the device is in its closed or locked position, the roller 15^a is placed between the 50 door-frame or jamb 5 and the tongue or lug 6, Fig. 3, thereby removing it out of the way, which position is accomplished by forming the tongue at or near the middle of the back or intermediate portion 2, as hereinbefore set forth. When it is desired, the spring can be quickly removed off of lug 6 and shaft or connecting-member 17, by simply detaching its hooked ends from said parts or members.

What we claim is:

55 1. A device of the character described, comprising a sheet-metal casing formed from a single piece and provided with sides and a back, said sides and back each provided with an apertured lug positioned at right-angles, 60 said back provided with an integral apertured lug formed at its center, said tongue positioned parallel with the sides, arms pivotally mounted upon the sides, a spring con-

nected at one end to the tongue, means connecting its opposite end to the arms near 65 their outer ends, yieldable rollers supported between and at the ends of said arms, one of said rollers being adapted to be positioned between an end of the casing and said tongue.

2. A device of the character described, 70 comprising a casing provided with sides and a back, said back provided with an integral tongue positioned parallel with the sides, arms pivotally mounted upon the sides, rollers supported upon the arms near their outer 75 ends, a spring connected at one end to the tongue, means connecting the opposite end of the spring to the arms, and one of the rollers adapted to be positioned near one edge of the tongue and between the sides of the 80 casing.

3. A device of the character described, 85 comprising a casing provided with sides and a back, said back provided near its center with a tongue, a pair of rollers, means rotatably supporting said rollers upon said sides, means connected to said roller-mounting means and tongue for exerting a pull upon said supporting means, and one of the rollers adapted to be positioned between the sides 90 and contiguous to the lug when the device is in a locked position.

4. A device of the character described, 95 comprising a casing formed from a sheet of metal and comprising a back and parallel sides, lugs at one and the same end of said sides and back, said back provided with a transverse tongue partly cut from its body intermediate its ends, said tongue positioned parallel with the sides, movable door-securing 100 means carried by said sides, and means connected with the tongue and said door-securing means for retaining it in a locked or unlocked position.

5. A device of the character described, 105 comprising a casing provided with a tongue intermediate its ends, door-securing means provided with a pair of rollers, pivotally mounted upon said casing, said rollers positioned at the ends of said door-securing 110 means, means connected to said tongue and said door-securing means for normally holding the door-securing means in a locked or unlocked position, and one of the rollers constituting a bumper when the door-securing 115 means is moved to an unlocked position, and said last-mentioned roller being adapted to be positioned between portions of the casing and contiguous to the tongue.

In testimony whereof we hereunto affix 120 our signatures in presence of two witnesses:

GEORGE L. ROBINSON.
JAMES DEAN.
